DESIGN FOR A BASE FOR A FLORAL BASKET OR SIMILAR ARTICLE

Roderic M. Koch, Evansville, Ind.

Application February 21, 1940, Serial No. 90,428

Term of patent 14 years

to all whom it may concern:

Be it known that I, Roderic M. Koch, a citizen of the United States, residing at Evansville, County of Vanderburg, and State of Indiana, have invented a new, original, and ornamental Design for a Base for a Floral Basket or Similar Article, which the following is a specification, reference being had to the accompanying drawing forming a part thereof.

Figure 1 is a perspective view of a base for a floral basket showing my new design.

I claim:

The ornamental design for a base for a floral basket or similar article, as shown.

RODERIC M. KOCH.
